SPRINKLER HEAD MODIFICATION

Jesse J. Robbins, Glendale, Calif., assignor to
Stylofede Corporation, Glendale, Calif., a corporation of California

Application September 20, 1946, Serial No. 698,145

1 Claim. (Cl. 299—18)

1

My invention relates to sprinkler heads and particularly to improvements therein whereby the area of fluid dispersion of the said sprinkler head might be regulated.

While sprinkler heads in general, and sprinkler heads of the general pop-up type, comprising a sprinkling valve adapted to the application of fluid pressure to raise above the ground and disperse fluid upon the surrounding area are not new, no simple yet inexpensive effective means has yet been found whereby the area of fluid dispersed about the sprinkler head might easily be varied.

It is the principal object of my invention to provide means insertable in a sprinkler head enabling the operator to effectively vary the area of fluid dispersion according to the area desired to be sprinkled.

It is my further object to provide a dispersion varying member, the insertion of which in a fluid sprinkler enables the operator to achieve a dispersing of fluid over either of two desired areas, depending upon the manner of insertion, and which when removed from the sprinkler head allows a full 360° dispersion.

It is another of my objects to provide such dispersion varying member of durable yet extremely inexpensive construction and adapted for insertion in a sprinkler head with a minimum of inconvenience.

Again it is my object to provide a sprinkler head adapted for receiving the aforesaid dispersion varying member and adapted to cooperate therewith in the dispersion of fluid over varying areas.

Other objects and advantages of my invention will be apparent from the following description of the preferred embodiments thereof. While the said following description shows my dispersion varying means in a sprinkler head of the pop-up type, it is easily adaptable for sprinkler heads of other types and varieties.

In the drawings:

Figure 1 shows in section a sprinkler head incorporating my invention.

Figure 2 shows a cross-sectional view of such sprinkler head taken along the line 2—2 of Figure 1.

Figure 3 shows a bottom plan view of my dispersion varying means.

Figure 4 shows a top plan view thereof.

Figure 5 shows a sectional view of my dispersion varying means taken on the line 5—5 of Figure 4.

Figure 6 shows in top plan a sprinkler system 55 40 is merely left out, and the fluid passes out of

2

incorporating my invention in its various manifestations.

Figure 7 shows an elevational view of a section of a sprinkler system pipe having mounted thereon one of my sprinkler heads.

Figure 8 shows a perspective view of my dispersion varying member.

Figure 9 shows a perspective view of my sprinkler head cap.

10 Referring to the drawings, a nut 2 has threads 4 which are adaptable for threading on pipe extension 6 comprising part of a sprinkling system 8. Slidable in the bore 10 of the nut 2 is a tubular member 12. The said tubular member 12 has a channel guideway 14 in which rides an extrusion 16 of the nut 2. The tubular member 12 is provided with the threads 18 with which coacts the threaded cap 20, having a bore 22 and orifices 24, 26, 28 and 29 leading therefrom and into a chamber 30 comprised of the enlarged bore 32 of the said tubular member 12. To prevent sliding by the tubular member 12 on through the nut 2, a groove 34 is provided in the tubular member 12 and receives a split annular ring 36.

25 Adapted to be received in the enlarged bore 32 of the tubular member 12 and to seat on the shoulder 38 thereof is the dispersion varying member 40. The dispersion varying member 40 comprises a tube, the lower end 42 thereof 30 adapted to seat on the shoulder 38 and the upper end 44 thereof abutting the tapering side of cap 20, or vice versa. To provide egress for water passing through the sprinkling system 8 through the pipe 6 and into the sprinkler head are cut-away portions of the dispersion varying members 46 and 48. These cutaway portions 46 and 48 are formed by cutting along lines drawn from the points 58 or 60, around the periphery of the said tube at one side, and terminating in out-swept 35 curves 50 and 52 or 54 and 56, respectively, at either extremity, the said curves intersecting the end edges of the said dispersion varying member. If desired, the line of cut may be tapered as shown in Figure 5 from the lowermost points 45 58 and 60 of the cutaway portions 46 and 48 outwardly towards the ends of the said dispersion varying member until terminated by the respective curves. Thus is formed in essence a tube somewhat biased at its ends, if desired, and having upraised annular segments 62 and 64 at either end for the purpose of directing the flow of fluid.

In operation where a full 360° area of fluid dispersion is desired, the dispersion varying member

the orifices 24, 26, 28 and 29 into the chamber 30 biasing outwardly against the tapered side of the cap 20 and distributing as at 66. Of course, as is well known, the particular type of sprinkler head shown, that is, the pop-up type, will slide upwardly in the nut 2 to the position shown in Figure 1 as a result of the pressure of the fluid entering the tubular member 12. Where it is desired to restrict the area of dispersion, the cap 20 is unthreaded from the tubular member 12 and the dispersion varying member 40 slid into the bore 32 and seated upon the seat 38 after which the cap 20 is replaced and threaded down until its tapering side abuts against the ends of the dispersion varying member. This directs the flow of water through either of the cutaway portions. As shown in Figure 5, in which the upraised annular segment 62 extends further about the periphery of the dispersion varying member 40 than does the upraised annular segment 64, the area of dispersion of the sprinkler head will depend upon whether the end 44 is uppermost within the sprinkler head or whether the end 42 is uppermost. Furthermore, the area of dispersion will be determined originally by the amount of the cuts 46 and 48. The more extensive annular segment remaining, the less extensive the area of dispersion.

For example, in order to achieve a 90° area of dispersion as shown at 70 and a 180° area of dispersion as shown at 72, both being particularly desired for lawn sprinkling purposes, I have constructed my dispersion varying member with the annular segment 62 comprising 137° of the periphery of the dispersion varying member 40 for 90° and the annular segment 64 comprising 69° of the periphery of the said dispersion varying member for 180°. In addition, I have biased the cuts 46 and 48 6° and the curves 50, 52, 54 and 56 are of $\frac{1}{2}$ -inch radius. The longitudinal distance between the point 60 and the end 42 is .078 inch, and the longitudinal distance between the point 58 and the end 44 is the same. In a dispersion varying member the length of which between ends 42 and 44 is .437 inch and the inside diameter of which is .421 inch, such configuration has enabled me to contrive a sprinkler head adaptable for distributing fluid about 360°, 180° or 90°, depending upon whether the dispersion

varying member is left out of the sprinkler head, is placed in same with the end 44 seating on the shoulder 38, or is placed therein with the end 42 seating on the said shoulder.

5 While I have described what is at present considered a preferred embodiment of the invention, it will be understood that various changes and modifications may be made therein without departing from the essence of the invention and it is intended to cover all such changes and modifications as come within the true scope and spirit of the appended claim.

I claim:

15 A sprinkler device comprising, a tube formed with an internal annular shoulder in spaced relation to an end thereof and having an internally threaded portion extending interiorly of said shoulder, a sleeve slidably mounted within said tube end and supported at one end on said 20 shoulder with its outer end projecting from said tube end, and a plug member having a disc-shaped head engaged on its under side with said outer sleeve end, said plug member having a hollow shank portion extending from said head and terminating in an enlarged threaded end threadably engaged with said threaded tube portion 25 thereby clamping the opposite ends of said sleeve between said head and said shoulder, said shank being spaced from said sleeve to define an annular discharge passage therebetween and being provided with openings communicating said 30 chamber with said tube interiorly of the last named end of said plug member, said outer sleeve end being cut away to provide a discharge opening at said under side of said head and at one 35 side only of said sleeve.
